EDWIN W. BULLARD, OF SPRINGFIELD, MASSACHUSETTS.

WHISTLE-OPERATING MECHANISM.

1,178,467.

Specification of Letters Patent.

Patented Apr. 4, 1916.

Application filed October 1, 1912. Serial No. 723,321.

To all whom it may concern:

Be it known that I, EDWIN W. BULLARD, a citizen of the United States of America, residing at Springfield, in the county of 5 Hampden and State of Massachusetts, have invented certain new and useful Whistle-Operating Mechanism, of which the following is a specification.

My invention relates to improvements in 10 sound-producing devices of the type known as whistles or horns and its application as shown herein is to the type of whistle or horn in which the sound is produced by the forcible ejection of air, gases, as the spent 15 gases from the exhaust of a gasoline engine, or equivalent medium, through constricted orifices, and in this instance the invention resides in certain peculiar electrically-operated means wherewith to constrict the opening 20 in the whistle whereby the sound is produced by the outrushing current of air, gas, or other medium, and to open such exit to an extent that no sound is produced by the aforesaid sound-producing medium, the 25 same being in addition to the ordinary means employed for a similar purpose and operated by hand or foot through mechanical connections.

In general my invention comprises the employment of magnets and solenoids for operating a movable member to cause it to occupy a position to cause the whistle to be sounded. A simple form of whistle or horn as shown herein as illustrating the application 30 of my invention consists of a body provided with a shutter, a second shutter or valve adapted to perform the same work as the first, an electro-magnet which may be mounted on said first-mentioned valve, and 35 means for operating said second valve by said magnet, all as hereinafter set forth.

Ordinarily whistles which are blown by the exhaust from the engine of an automobile are operated by mechanical means connected with a suitably-located foot or hand lever, but it is desirable to operate such whistles from the steering post or wheel or some other equally convenient point and to operate them by electrical means, for obvious 40 reasons, the object of my invention, therefore, is to provide a whistle with elec-

trical operating means, and this by preference being in addition to the ordinary mechanical operating means, to the end that the operator may sound the whistle from a 55 point most convenient to his hand, by simply pressing a button, and may also sound the same by mechanical means, so that he may resort to either one of two independent actuating or operating mediums. 60

A further object of my invention is to produce means for electrically operating whistles, which means is comparatively simple and inexpensive and can without difficulty be incorporated with a whistle of ordinary construction. 65

Other objects will appear in the course of the following description.

I attain the objects of my invention by the means illustrated in the accompanying 70 drawings, in which I show one practical embodiment of my invention, and in which drawings—

Figure 1 is a side elevation of a whistle or horn equipped with one form of my improved operating mechanism, both shutters in this view being shown open. Fig. 2 is a longitudinal vertical section through said whistle or horn and its associated parts, and in which the electrically operated shutter 75 is shown in its closed position. Fig. 3 is a sectional view similar to Fig. 2 except that the electric operating mechanism is shown in elevation and the mechanically operated shutter is shown in its closed position, the 80 electrically operated shutter being also closed, the closing of the latter shutter, however, being incidental to the closing of the mechanically operated shutter; and Fig. 4 is an end elevation of the device shown in 85 Fig. 1. 90

Similar figures of reference indicate similar parts throughout the several views.

First describing briefly the old and well-known elements which are utilized in this 95 embodiment of my invention, and then following with a detailed description of the new features as here illustrated, and afterward describing the operation of the device as a whole, referring to the drawings, I show 100 a horn or whistle consisting of a casing divided into two parts, viz: rear and front

chambers, an opening being provided in the upper side of said casing which extends both in front of and at the rear of the substantially vertical partition as indicated at 5—5.

5 The casing 1 is designed to be attached to the exhaust conduit of an automobile engine, the discharge of gases or other fluid being into the chamber 3, and when the device is not being sounded, through the opening in 10 the top of said chamber. If, however, this opening be closed by means of the shutter 6 the orifice being restricted causes the device to give forth sound in the well known manner. By preference the shutter 6 has depending side pieces 8—8 which fit the sides 15 of the casing 1, and their rear portions are pivotally attached at 9 to said casing. The shutter 6 is normally retained in its open position by a spring or other equivalent means, 20 and is closed mechanically by means which may be operated by foot or hand, such means being transmitted through proper operating mechanism.

Rigidly attached to the top of the casing 25 behind the opening therein is an upright or support 13. A spring 14 has its ends respectively attached to the support 13 and the plate 12 at their upper terminals and normally retains the valve 6 in its elevated 30 or open position, as shown in Figs. 1, 2 and 4. The upward movement of the valve 6 is here limited by means of an electro-magnet or solenoid 15, the upper rear edge of which comes in contact with the support 13 and so 35 limits the movement of said valve under the influence of the spring 14.

The solenoid 15 has a plunger 16 which is centrally bored to receive a spring 17 and a guide rod 18 that extends inwardly from 10 the inner face of a fixed part 19 of the core of which said plunger is also a part. The tendency of the spring 17, which spring is located between the inner end of the rod 18 and the adjacent end of the passage in which 15 said spring and rod are received, is to force the plunger 16 outwardly or rearwardly so as to form a gap between adjacent ends of said plunger and the part 19, and although light said spring has sufficient power not 20 only to actuate the plunger but also the members which are operated by the plunger. Extending rearwardly from the exposed end of the plunger 16 is a headed post 20. At 21—21 appear portions of the circuit-forming wires which are attached to the solenoid. The electrical energy is derived either from batteries or a magneto, as in other cases where such energy is employed in and about 25 automobiles.

60 Nested within the valve 6 and its side pieces 8 and having said valve superimposed is a second valve 22 provided with side pieces 23—23. The rear terminals of the side pieces 23 are mounted on the pivot 9 inside

of the side pieces 8. The valve 22 is designed and adapted to close the opening in the chamber 3 and to form the orifice 7 in precisely the same manner as does the valve 6, or as the latter would close such opening in the absence of said valve 22. The 70 valve 22, which is in the path of the valve 6, first comes to rest on the side edges of the opening in the top of the chamber 3, and the valve 6 comes to rest on top of said valve 22, when the valve 6 is the one used or operated 75 for producing the sound, as clearly shown in Fig. 3. In the absence of the valve 22, the valve 6 would come to rest directly on the upper edges of the sides of the opening in 80 the chamber 3 and became a direct factor in the formation of the orifice 7, as hereinbefore intimated and as is the case in the old construction. Rigidly attached to the rear end or edge of the valve 22 is an upwardly and rearwardly extending arm 24 which has a head 25 at its free end to be received between the head of the post 20 and the adjacent end of the plunger 16. The arrangement of parts is such that when the plunger 16 is thrust outwardly by the spring 17 90 it carries with it the arm 24 and so causes the side pieces 23 to turn on the pivot 9 and the valve 22 to be swung upwardly against the underside of the valve 6, and that when said plunger is drawn inwardly under the 95 influence of the magnetism produced when an electric current is passed through the solenoid 15 said valve 22 is swung downwardly into position to form the orifice 7 through the same medium as before, the oscillating parts moving on the pivot 9. The head 25 of the arm 24 follows the plunger 16 in both cases. There is a slot or recess 26 in the support 13 for the accommodation 100 of the post 20 and the arm 24.

105 Since both valves and the solenoid are mounted on the same pivot it is obvious that when said valves are drawn down or closed by means of the link 10 no change in relation takes place between the plunger 16 and the arm 24.

With the parts standing as shown in Fig. 1 the complete operation of the whistle and its mechanism is as follows: If it be desired 115 to blow the whistle by the mechanical means that operates through the link 10, the proper action is taken or movement made to draw down said link and so swing downward both valves 6 and 22 against the resiliency of the spring 14, to form the orifice 7, as shown in 120 Fig. 3. Normally the spring 14 retains the valve 6 in open position and the spring 17 performs a like office for the valve 22, so that both valves are in contact and both move down with the link 10. So long as 125 the valves are retained in the closed position just referred to the whistle is sounded, assuming, of course, that the necessary

sound-producing element is being forced through the same, and upon the release of the link so that the parts which are under the influence of the spring 14 can swing upwardly upon the pivot 9 the sound ceases, because the opening thus made by the moving away of the valves from the upper edge of the partition 2 is large enough for the sound-producing element to escape noiselessly.

When the whistle is to be operated electrically, as by pressure on a push-button located on the steering-wheel or steering-post, the energized solenoid 15 causes the plunger 16 to move inwardly, against the resiliency of the spring 17, and to carry with it the head of the arm 24, with the result that the valve 22 is swung downwardly into closed position, as shown in Fig. 2. The valve 22 moves downward away from the valve 6 and independently thereof. The whistle now sounds and continues to sound until the controlling push-button or other form of switch is released, when such sound ceases, because then the deenergized solenoid releases the plunger 16 to the spring 17 and the latter forces said plunger outwardly, and, through the medium of the arm 24, causes the valve 22 to be actuated upwardly against the valve 6, thus making a clear and practically unobstructed passage for the noise-producing element.

Although I have herein shown and described a practical form of embodiment of my invention, it is clearly to be seen that other forms may be employed without departing from the spirit of said invention, and especially is it apparent that substantial changes in the shape, size, construction, location and arrangement of some or all of the parts may be made without exceeding the scope of my claims, for which reason I do not desire to be limited in any way to the particular construction herein set forth in detail.

What I claim as my invention, and desire to secure by Letters Patent, is—

1. The combination, with a whistle or horn casing having an exit opening therein and a fixed member adjacent to such opening, of an electrically-operated member adapted to coöperate with said fixed member for the purpose of forming a sound-producing aperture, and a mechanically-operated member arranged and adapted to form such aperture, said fixed member together with said movable members forming between them the sound producing orifice.

2. The combination, with a whistle or horn casing having an exit opening therein and a fixed member adjacent to such opening, of an electrically-operated member arranged and adapted to coöperate with said fixed member for the purpose of forming a

sound-producing aperture, and a mechanically-operated member similarly arranged and adapted as is said electrically-operated member, said last-named member being in the path of said mechanically-operated member.

3. The combination, with a whistle casing having an exit opening therein and provided with a fixed member adjacent to such opening, of two shutters mounted adjacent to such opening and to such fixed member, one of such shutters being adapted to be operated independently of the other or in conjunction with the other as the case may be, electrically-operated means for the independent shutter and mechanically-operated means for the other shutter.

4. The combination, with a whistle casing having an opening therein and provided with a fixed member adjacent to such opening, of an inner shutter pivotally mounted adjacent to such opening and to such fixed member, electrically-operated means for said shutter, an outer shutter also pivotally mounted on said casing, and mechanically-operating means for said outer shutter, said inner shutter being in the path of said outer shutter.

5. The combination, with a whistle or horn casing having an exit opening therein and provided with a fixed member adjacent to such opening, of operating mechanism comprising two shutters mounted adjacent to such opening and to said fixed member, mechanically-operating means for one of such shutters, and electrically-operated means for the other of such shutters, said electrically-operating means being mounted on the mechanically operated shutter.

6. The combination, with a whistle casing having an exit opening therein and provided with a fixed member adjacent to such opening, of operating mechanism comprising outer and inner shutters pivotally mounted on said casing adjacent to such opening and to such fixed member, resilient means arranged to normally retain both said shutters in open position, and means to actuate the inner or both of said shutters into closed position.

7. The combination, with a whistle casing having an exit opening therein and provided with a fixed member adjacent to such opening, of operating mechanism comprising outer and inner shutters pivotally mounted on said casing adjacent to such opening and to such fixed member, resilient means to normally retain both said shutters in open position, mechanically-operated means arranged to close both of said shutters, and electrically-operated means mounted on said outer shutter and adapted to close said inner shutter independently of said outer shutter.

8. The combination, with a whistle or horn casing having an exit opening therein and provided with a fixed member adjacent to such opening, of operating mechanism comprising inner and outer shutters movably mounted adjacent to such opening, resilient means adapted to normally retain said outer shutter in its open position, a solenoid mounted

on said outer shutter and having a spring-pressed plunger, and an arm carried by said inner shutter and operatively engaged with said plunger.
